UNITED STATES PATENT OFFICE.

CHARLES BASHWINER, OF JAMAICA, NEW YORK, ASSIGNOR TO FORT ORANGE PAPER COMPANY, OF CASTLETON, NEW YORK, A CORPORATION OF NEW YORK.

DISPLAY BOX.

Application filed January 12, 1922. Serial No. 528,834.

To all whom it may concern:

Be it known that I, CHARLES BASHWINER, a citizen of the United States, residing at Jamaica, borough and county of Queens, 5 city and State of New York, have invented new and useful Improvements in Display Boxes, of which the following is a specification, reference being had to the accompanying drawings, in which

10 Fig. 1 is a plan of a blank cut so as to be folded into a box embodying my invention; Fig. 2 is a perspective showing the box partially folded; Fig. 3 is a sectional detail view of the support; Fig. 4 is a perspective 15 of the box in display position; and Fig. 5 is an elevation of the box with the cover on.

20 My invention relates to display boxes or containers which are cut out of a blank of cardboard or similar material and folded to form a box suitable for the display of its contents. To this end I have provided a box 25 made from a single sheet or piece of material, which when cut and folded forms a box and cover in a single piece, the cover being capable of being used not only as a cover when the box is closed, but also as a support for the box when the box is in display position. The blank is also so cut and folded that all 30 the painting or decorating which it is desired to put on the box may be placed on one side of the blank, and when the blank is folded the printed matter will appear on the visible portions of the box in both display 35 and closed positions. My invention also comprises the various features which I shall hereinafter describe and claim.

35 Referring to the drawings, the box blank is cut and scored from a sheet of cardboard or similar material in the manner shown in Fig. 1, in which the scoring is indicated in dotted lines and the cutting in uninterrupted lines. The numeral 2 indicates the bottom of the box, 3 and 4 the outer sides, and 40 5 and 6 the outer ends, all of which are attached directly to the bottom 2. Extending outwardly from the outer sides 3 and 4 are the inner side members 7 and 8, respectively, which at corresponding ends have attached 45 thereto the pieces 9 and 10, respectively, which serve to reinforce the forward end of the box. Also attached to the side piece 8 is an end piece 11 which reinforces the rear 50 end of the box, and depending from this 55 is a flap 12 which extends around to the op-

posite side and forms a reinforcement and lock between that side and the rear end.

Attached to the sides of the end pieces 5 and 6 are the flaps 13 and 14 and 15 and 16, respectively. When the box is folded, the 60 flaps 13 and 15 lie between the side pieces 3 and 7, and the flaps 14 and 16 lie between the side pieces 4 and 8, thus reinforcing the four corners of the box. Extending outwardly from the end piece 5 is the end piece 65 17, which terminates in a strengthening strip 18.

At the rear end of the box and forming a continuation from the end piece 6 is a supporting piece 19, to which is hinged a hinged 70 section 20, which forms part of the cover and the connection with the support portion. The main part of the support portion is the piece 21, which has at its sides wings 22, each of which carries the outwardly extending foldable sections 23 and 24 and a forwardly extending section 25. At the outer end of the part 21 is the end 26 of the support, which has attached thereto the foldable sections 27 and 28, which serve to lock the 80 parts of the support together. Attached at one side of the member 19 is a display member 29, which has a foot 30, which serves to hold the display member erect when in display position.

85 Any printing or advertising matter which it is desired to have upon the box may be applied to the underneath side of the blank, as shown in Fig. 1, and when the box has been folded into box form it will be found 90 that the printing will appear on the displayed and visible surface of the box.

For reinforcing purposes the box is slotted at 31 along the line of scoring, between the parts 2 and 6, for the reception of a 95 tongue 32, which projects rearwardly from the part 21. The part 21 is also cut to form a tongue 33, which acts as a lock for the strip 28.

100 In assembling the box, either the support or the container proper may be first folded into position, but I will describe the forming operation by first folding the support and then the container.

105 The strips 24 are first bent at right angles to the strips 23 and the sections 23 are folded back on the sections 22, and the sections 22 are bent up at right angles to the part 21. The extensions 25 are then folded in to overlap each other. The part 26 is bent at 110

- right angles to the part 21, and the section 27 is bent down over the extensions 25 and the strip 28 is locked under the tab 33, thus securing the parts of the support together. 5 The display section 29 is next folded inwardly upon the parts 19 and 20, with the supporting foot 30 upon the end piece 6. The container is assembled by folding the end parts 5 and 6 at right angles to the 10 part 3, with the projections 13, 14, 15 and 16 folded into position along the lines of division between the sides 3 and 4 and bottom 2 of the box. The side 8 is then folded inwardly over the projections 14 and 16, carrying with it the end portions 10 and 11 and the flap 12, which is later to bear against the inner face of the side piece 3. The side portion 7 is then folded inwardly over the projections 13 and 15, carrying with it the 20 end reinforcing portion 9. The end piece 17 is then folded down over the end reinforcing members 9 and 10 until the strip 18 seats flat on the bottom of the box, which complete the forming operation. 25 The box may then be filled and the support folded over it as a cover, as is shown in Fig. 5. When it is desired to display the contents of the box the support is folded rearwardly, in which case the part 19 assumes an erect position, substantially as a 30 continuation of the rear end 6, while the part 20 is folded downwardly at an angle approximating 170° along the scoring and permits the insertion of the tab 32 in the 35 slot 31, so that the tab 32 may be pushed upwardly between the inner end wall 11 and the outer end wall 6. The support pivots forwardly along the line of scoring between the part 20 and the 40 part 21 until the part 21 is directly under and supports the rear end of the box in an elevated position, so that the contents of the box are readily visible and the display section stands erect at the elevated end of the box. 45 The support is preferably trapezoidal in form and gives an extended bearing on the base and an extended inclined bearing on the bottom of the box so as to ensure the stability of the box in its display position 50 and the maintenance of the box on an in-

cline so that its contents are exposed to view.

The terms and expressions which I have employed are used as terms of description and not of limitation, and I have no intention, in the use of such terms and expressions, of excluding any equivalents of the features shown and described, or portions thereof, but recognize that various modifications are possible within the scope of the invention claimed.

What I claim is:

1. A display box comprising a container having more than one ply of material in each of its sides and ends, a display member, a combined cover and support therefor, and a flexible connection between container and support, the connection being integral with one of the plies of material at the rear end of the box, and when the container is in display position extending from a position at a distance above the rear end of the box to the highest part of the support, a backing member also extending above the top edge of the box arranged to hold the display member in erect position, the said display member having a depending portion interposed between two of the plies of material at the rear end of the box. 75

2. A display box comprising a container having more than one ply of material in each of its sides and ends, a display member, a combined cover and support therefor, and a connection between container and support, the connection being integral with one of the plies of material at the rear end of the box, and when the container is in display position extending from a position at a distance above the rear end of the box to the highest part of the support, a backing member also extending above the top edge of the box arranged to hold the display member in erect position, the said display member having a depending portion interposed between two of the plies of material at the rear end of the box, and a slot and projection engagement between support and container for locking the support beneath the container. 90 95

CHARLES BASHWINER.
